(57) **CLAIM**

The ornamental design for a water tank for hair straightening apparatus, as shown and described.

DESCRIPTION

FIG. 1 is an isometric view of a water tank for hair straightening apparatus showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof;

FIG. 7 is a bottom view thereof;

FIG. 8 is an isometric view of a bottom portion of the water tank for hair straightening apparatus of FIG. 1, shown removed for ease of illustration.

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top view thereof;

FIG. 14 is a bottom view thereof;

FIG. 15 is an isometric view of a top portion of the water tank for hair straightening apparatus of FIG. 1, shown removed for ease of illustration.

FIG. 16 is a front elevational view thereof;

FIG. 17 is a rear elevational view thereof;

FIG. 18 is a right side elevational view thereof;

FIG. 19 is a left side elevational view thereof;

FIG. 20 is a top view thereof; and,

FIG. 21 is a bottom view thereof.

(Continued)

The broken lines shown in the figure drawings depict portions of the water tank for hair straightening apparatus which form no part of the claimed design.

1 Claim, 18 Drawing Sheets
